UNITED STATES PATENT OFFICE.

HARRY Y. ARMSTRONG, OF SPRINGFIELD, MASSACHUSETTS, ASSIGNOR OF ONE-HALF
TO WILLIAM L. HALL, OF CHICAGO, ILLINOIS.

ENVELOP-MAKING MACHINE AND METHOD.

1,367,291.

Specification of Letters Patent.

Patented Feb. 1, 1921.

Application filed February 11, 1918. Serial No. 216,446.

To all whom it may concern:

Be it known that I, HARRY Y. ARMSTRONG, a citizen of the United States, and a resident of Springfield, in the county of Hampden 5 and State of Massachusetts, have invented certain new and useful Improvements in Envelop-Making Machines and Methods; and I do hereby declare that the following is a full, clear, and exact description thereof, reference being had to the accompanying 10 drawings, and to the characters of reference marked thereon, which form a part of this specification.

This invention relates to improvements in 15 the art of making envelopes and refers to a method of producing envelopes and a machine for making them. The invention is herein shown as designed to produce the type of envelop illustrated in my pending 20 application for United States Letters Patent Serial Number 163,871, filed April 23, 1917, wherein the envelop is made from a single piece of paper embracing equal dimension front and rear sections folding one 25 upon the other and pasted at their end margins and open at one side, one of the sections being provided with a terminal closing flap to be folded flat on the other section and pasted thereto. The invention is 30 adaptable to envelopes of other design.

In producing an envelop in accordance with my invention, a sheet or web of paper is unrolled from a roll of paper, supported on a reel, and the paper, as it leaves the roll, 35 tends to assume a permanent set, due to the spiral formation of the web on the roll. Said web is thereafter so manipulated in folding it to produce the envelop, that advantage is taken of this set in the paper 40 web when the layers are brought together to ultimately constitute the walls of the envelop, as to cause the spring imparted to the paper web to tend to force the walls away from each other at their central portions or 45 between their pasted margins.

In practising my invention, the web of paper is so drawn from the roll and is so manipulated thereafter in folding it and directing it to the folding means that the 50 outer face of the web, as it leaves the roll, becomes the outer faces of the walls of the envelop tube and of the walls of the complete envelopes; and the set of the paper is such as to cause said walls to spring away

or bulge from each other between their 55 pasted margins.

The machine herein shown embraces means to longitudinally fold a strip or web of paper, means to paste the layers of the tube together at longitudinal intervals coincident with the lengths of the envelopes and to finally sever the folded pasted tube into envelop lengths at said pasted areas.

The invention consists in the combination and arrangement of the parts shown in the 60 drawings and described in the specification, and is pointed out in the appended claims.

I have shown in the drawings the elements of the machine for making envelopes in accordance with the present invention, 70 said elements being diagrammatically shown, but sufficiently to illustrate the principle of the invention.

As shown by said drawings,

Figure 1 is a perspective, diagrammatic 75 view illustrating the manner of taking the web from the supporting roll, and for guiding it to the folding mechanism, showing the mechanism for folding the web, for applying paste patches thereto, and for severing 80 the folded web or tube to produce the complete envelops.

Fig. 2 is a section on the line 2-2 of Fig. 1, illustrating the folding horn by which the web is longitudinally folded to 85 produce the envelop tube.

Fig. 3 is a plan view illustrating the folded web and the position of the folding horn relatively thereto.

Fig. 4 is an enlarged view of the flat web 90 showing the spacing of the paste patches applied theron.

Fig. 5 is an enlarged perspective view of the parts shown in Fig. 4.

Fig. 6 is a perspective sectional view of 95 the envelop tube.

Fig. 7 illustrates a complete envelop.

Fig. 8 is a longitudinal section of the envelop.

As shown in the drawings, and referring 100 more particularly to Fig. 1, 10 designates a reel on which a roll of the paper web is supported. 11, 12, designate lower and upper scoring rolls, respectively, located in advance of said reel 10 and between which the 105 web, after it leaves the reel, is trained. The lower roll is provided with circumferentially continuous, spaced scoring knives 14 and the

upper roll is provided opposite to the scoring knives with circular grooves 15 to cooperate with said knives. 16 designates a paste applying roll which is provided with oppositely disposed paste applying members 17 of suitable length to apply paste patches to the sheet or web. These paste applying members receive paste from a transfer roll 18 that rotates partially submerged in a body of paste in a paste pot 19. Said rolls 11, 12, 16, and 18 will, in practice, be geared to operate in proper sequence to apply the paste patches P to the web at suitable spaced intervals corresponding to the width of the envelopes.

Located above said scoring rolls is a guide roll 20 which is obliquely disposed at an angle of about 45 degrees to the planes of the axes of the roll shafts.

20 22, 23 designate upper and lower drawing rolls, respectively, which are arranged in advance of the oblique guide roll 20, 24, 25 designated printing rolls, if it be desired to print a return address or like subject 25 matter on the envelopes. 26, 27 designate upper and lower cutting or severing rolls by which the envelop tube is transversely severed to produce envelopes.

Located between said drawing rolls and 30 the oblique guide roll 20 is a horizontal V shape folding horn 30, and a symmetrically disposed V shape folding form 31 is disposed parallel to the folding horn as shown in Fig. 2. Said folding horn lies within the 35 form and the tapered edge thereof is directed toward and is located closely adjacent to the inner angle of said form.

The web W from which the envelopes are 40 made is somewhat more than twice the width of the completed envelop E shown in Figs. 6 and 7, and is folded upon itself along the score line e' to produce the front and back wall sections E', E² of the envelop, the dimensions of which are equal to 45 each other. The sections of which the front walls constitute a part are continued beyond the side edges of said sections to form closing flaps E³.

The drawing rolls 22, 23 serve, in addition 50 to drawing the paper from the machine, as means for effecting the first or initial squeezing of the paste patches P between the layers of the envelop tube, said patches being applied to the sheet by the paste applying members 17. For this purpose the upper drawing roll is provided with diametrically opposed limited squeezing areas 32 which act against the face of the lower roll, and said squeezing areas are flanked by parallel relief grooves 33, the purpose of which is to limit the squeezing action of the rolls on the paste patches.

The upper severing or cutting roll 26 is provided with diametrically opposed knives

34, disposed lengthwise of the roll, and fixed 65 in longitudinal grooves in the roll, with their edges extending slightly beyond the periphery thereof, and said knives are adapted to enter longitudinal grooves 35 in the lower roll 27 in cutting relation to the walls 70 of said grooves. Said knives cut the individual envelops from the envelop tube. Clamping bars 36 are set in grooves in said upper roll which grooves are disposed in planes obliquely to the knife grooves, and 75 backed by springs 37, which serve to clamp or hold the envelop tube between the same and the lower roll 27 during the cutting operation. Said bars also serve to clean the knives of paste which tend to adhere thereto, the knives severing the envelop tube through the paste patches. The severed envelops are carried away from the machine between the adjacent laps of take-off belts 38.

80 The operation of the machine is as follows:

The paper web W is drawn from the upper side of the roll on the reel 10 and as it passes between the rolls 11 and 12 said web 90 is scored to produce score line e¹, e², on the former of which the web is folded to produce the front and rear walls E¹, E² of the envelop and on the latter of which the marginal portion or flap E³ is folded. As the 95 web passes the paste applying roll 16 the paste applying members 17 contact with that surface of the web which, as the web leaves the roll, is the inner surface; said paste patches being applied at distances 100 apart equal to the width of the complete envelops. The web is directed by the oblique roll 12 to the folding horn 30 and form 31, which latter serve to produce the envelop tube E⁴ shown in Fig. 3; the paste patches 105 appearing between the layers of said tube. The drawing and squeezing rolls 22, 23 are so timed that the squeezing areas 32 are always presented to the paste patches to press the layers of the envelop tube thereon. The folded web is advanced by said rolls 22, 23 and, if the printing rolls 24, 25 be presented, the tube is printed as it passes therebetween. The cutting or severing rolls 26, 27 are so timed as to bring the cutting knives 110 always in position to sever the tube at the paste patches, the paste patches being of such width that when severed paste areas of sufficient width will be left between the end margins of the envelop walls.

115 From a consideration of Fig. 1 it will be noted that the outer face of the web as it leaves the roll becomes the outer faces of the walls of the tubes when folded over the horn 30, and, therefore, the outer faces of the 120 walls of the envelops when cut from the tube. The set of the paper produced by the spiral winding thereof around the roll, as

before stated, has the effect to cause the walls to tend to separate and produce the bulging effect shown in Fig. 8.

I claim as my invention,—

- 5 1. The method of making envelopes which comprises the steps of drawing a web from a spirally wound roll, and thereafter longitudinally folding the uncut web on itself to produce a continuous envelop tube and
- 10 10 transversely cutting said tube all in such manner that the outer face of the web, as it leaves the roll, becomes the outer faces of the complete envelop walls.
- 15 2. The method of making envelopes, which comprises the steps of drawing a web from a spirally wound roll, longitudinally folding the uncut web to produce a continuous envelop tube with the outer face of the web, as it leaves the roll, constituting the outer
- 20 20 faces of the walls of the tube and transversely severing the tube to produce complete envelopes.
- 25 3. The method of making envelopes, which comprises the steps of drawing a web from a spirally-wound roll, longitudinally folding the uncut web to produce a continuous envelop tube with the outer face of the web, as it leaves the roll, constituting the outer faces of the walls of the tube, transversely pasting
- 30 30 said tube walls together at longitudinally spaced intervals and transversely severing the tube at the pasted areas.

4. In an envelop making machine, a reel to support a roll of paper web, with means to longitudinally score the web means for 35 applying transversely patches of paste there-to at intervals and other means to thereafter fold the continuous web along the score line, means to transversely paste the folded web, and means for so directing the web to the 40 folding means that the exterior face of the web as it leaves the reel becomes the outer faces of the envelop structure when it is folded.

5. In an envelop making machine, a reel 45 to support a roll of paper web, drawing and forming means to produce a continuous unbroken envelop tube, means to transversely paste the tube walls at longitudinally spaced intervals, severing means to sever envelopes 50 therefrom, means between the reel and drawing and forming means to apply transverse paste patches to the web, and a guide roller between the reel and drawing and forming means arranged to direct the outer face of 55 the web as it leaves the roll to said drawing and forming means so that said outer face of the web becomes, in the envelop tube, the outer faces of the members of the tube.

In testimony whereof I claim the foregoing as my invention, I hereunto append my signature at Springfield, Massachusetts, this 6th day of February, 1918.

HARRY Y. ARMSTRONG.
